UNITED STATES PATENT OFFICE.

JOHN J. GISEKE, OF CHICAGO, ILLINOIS.

COLLAPSIBLE CRATE.

1,192,415.

Specification of Letters Patent. Patented July 25, 1916.

Application filed August 25, 1915. Serial No. 47,362.

To all whom it may concern:

Be it known that I, JOHN J. GISEKE, a citizen of the United States, and a resident of the city of Chicago, in the county of 5 Cook and State of Illinois, have invented a certain new and useful Improvement in Collapsible Crates; and I do hereby declare that the following description of my said invention, taken in connection with the accompanying sheets of drawings, forms a full, clear, and exact specification, which will enable others skilled in the art to which it appertains to make and use the same.

My invention relates generally to improvements in collapsible crates, and it consists, essentially, in the novel and peculiar combination of parts and details of construction, as hereinafter first fully set forth and described and then pointed out in the 20 claims.

In the carrying out of my invention one desideratum stands predominant, and that is a collapsible crate which may be converted from its operative condition into a compact 25 collapsed structure without the removal of any loose parts, members, or elements of any kind. In other words all the components producing my invention are always connected to a part of the structure whether in 30 knocked down or in upstanding or righted position, operative for the purposes intended.

In the embodiment of the invention are included means whereby two lifting movements of the hands "rights" the crate; and, 35 there are provided a plurality of finger tripped locks, positively locking the crate in its "righted" or operative position. Also included in my invention are features of construction whereby the entire crate may be, 40 and is preferably produced from light sheet metal and wire screen, so called, so that a long lived, light, strong, and cheaply manufactured article of manufacture is the resultant.

45 Briefly, my invention comprises a sheet metallic bottom floor or pan possessed of longitudinal and end upstanding walls, near the upper edges of which walls are provided hinge lugs. To the hinge lugs of the 50 end walls are hinged crate ends which are of a size equal to the interior width and height of the crate and are adapted to be "swung" inwardly about their hinges, so as to overlie the bottom in a plane parallel and adjacent thereto. To the hinge lugs on the longitudinal walls of the bottom are hingedly

attached the crate sides. These crate sides are made up of an even plurality of horizontally hinged together panels, and to the uppermost of these panels on each side of 60 the crate is hingedly connected an integral top member of substantially the same size as the bottom. Thus when the crate sides are forced inwardly, the panels thereof fold upon each other and overlie the crate ends 65 in close adjacency; and the single top member overlies the folded together sides as hereinafter more fully pointed out.

Located near the vertical edges of the 70 crate sides and the crate ends are coöperating devices adapted by "trips" of the fingers, to lock the four vertical corners of the crate into fixed relationship when in "righted" or operative position.

Referring now to the drawings herein 75 and made a part hereof, which serve to illustrate my invention more fully, Figure 1 is a side elevation showing the crate in its "righted" or operative position. Fig. 2 is a like elevation denoting the same in its 80 knocked down or collapsed position. Fig. 3 is an elevation of the end of the case in its "righted" position and Fig. 4 a similar elevation showing the crate as collapsed. Fig. 5 is a view of a fragment, taken from the 85 interior of the case and looking toward one of the crate ends showing a side elevation of the coöperating means for locking the sides and ends together. Fig. 6 is likewise a fragmentary view, looking at the parts 90 disclosed in Fig. 5 from the side of the crate and exteriorly thereof. Fig. 7 is a section in line 7—7 of Figs. 5 and 6. Figs. 8 and 9 are elevations of fragments similar in 95 nature to Figs. 5 and 6, but showing a modified form of the corner locking means. Fig. 10 is a plan of the invention. Fig. 11 is a transverse, vertical section of the bottom of my crate, taken at line 11—11 of Fig. 1. Fig. 12 is a longitudinal, vertical section of 100 said bottom in line 12—12 of Fig. 3. Fig. 13 is a section on an enlarged scale in lines 13—13 of Fig. 1 or Fig. 10. Fig. 14 is also an enlarged section, taken in line 14—14 of Fig. 1. Fig. 15 is likewise an enlarged section taken in line 15—15 of Fig. 10. Fig. 16 is an enlarged vertical, transverse section of a fragment of the crate in line 16—16 of Fig. 1, the crate end, however, being shown in knocked down or horizontal position. Fig. 17 is an enlarged vertical longitudinal section of a fragment of the crate 110

in lines 17—17 of Figs. 3 and 16; a portion of one of the crate ends and sides being indicated in collapsed or horizontal position.

Like parts are indicated by corresponding symbols or characters of reference in all the figures of the drawings.

The character A in the drawings indicates my crate in its entirety, whether righted or collapsed, while B denotes the bottom as a whole, and C the top of the crate.

The letter E designates in general the two ends of the structure, and F the two sides thereof, comprised of their plurality of hinged together panels, hereinafter more fully set forth.

Specifically describing the bottom B; it comprises first a rectangular blank 10 of light sheet metal having along the longitudinal edges thereof upstanding walls 11 and 11^a, bent up from and integral with said blank. In like manner the said blank has along its transverse or end edges similar upstanding walls 12 and 12^a, also integral with and bent up from said blank. Riveted or otherwise fastened to the longitudinal walls 11 and 11^a are sheet metallic substantially U-shaped troughs 13 and 13^a, the overall lengths of which troughs slightly exceed the overall length of the bottom B, to permit of end members 14 and 14^a to close the ends of said troughs and to be riveted or otherwise fastened to the end walls 12 and 12^a as seen in Fig. 12. The said end members are possessed of lips 15 and 15^a projecting into said troughs and adapted to be soldered or riveted thereto to provide tight joints at the ends of said troughs, and it may now be stated that the office of these troughs is to provide receptacles for food and water when my invention is employed as a live poultry shipping crate.

Projecting upwardly from the members 14 and 14^a, intermediate of their length are a plurality of hinge lugs 16 for the hinged reception of the crate ends E, to be more fully described.

Stiffening the sheet 10 of the bottom B and the troughs 13 and 13^a are provided a plurality of transverse metallic bands 17 Figs. 3 and 4, extending from the outer upper edge of one of said troughs, exteriorly around the same, underneath the sheet 10 and around the exterior of the other of said troughs. And, at the opposite ends of said bands, above the outer upper edges of said troughs 13 and 13^a, are formed hinge lugs 18 to be more fully referred to.

Having now reference to the crate ends E, seen particularly in Fig. 3 the same are made from wire screens 19 of proper size of wire and dimensions of mesh. The vertical and top edges of these screens are embraced by U-shaped sheet metallic strips 20, and the lower edges thereof by similar U-shaped strips 21; the latter, however, having

notched therein certain cut outs 22, so spaced as to register with the hinge lugs 16 of the bottom end members 14 or 14^a. Before affixing these strips 21 to the wire screen 19, pintles 23 are lodged in the bottom thereof and then the said strips are slipped over the lower margins of the wire screens and fixed in place, and it will now be observed that the pintles 23 pass through the cut outs 22, and, that these two elements form the components coöperating with the hinge lugs 16 to hingedly affix the crate ends E to the bottom B. In the manufacture of these ends, what is known as black wire screen is employed; the U-shaped marginal strips 20 and 21 are of black sheet metallic stock and are closely pinched or pressed about the ends of the screen, after which the frictionally united structure is dipped into a galvanizing bath, whereby the said strips and the screen are firmly united together. Attention is now directed to the fact that the hinge lugs 16 are disposed at such an elevation that the crate ends E will rest upon the marginal walls 11 and 11^a of the bottom B when said ends are swung into substantially horizontal position as seen for instance in Fig. 16. Medially of the width of the crate ends E are provided upright stiffening strips 24 to prevent the wire screens 19 from bulging under internal stress or external impact, in a manner easily understood.

The crate sides F are each comprised of upper and lower panels 25 and 25^a, respectively, which panels are duplicates of each other and may be described in the singular. Each panel is composed of a wire screen 26, bound along its vertical edges by U-shaped sheet metallic strips 27, and along its longitudinal edges, both top and bottom by U-shaped strips 28, having pintles 28^a which strips are possessed of cut outs or notches 29, which cut outs or notches are provided for double hinge or articulating members 30, seen particularly in Figs. 13, 14, and 16. The panels 25 and 25^a are connected together by these double hinge members 30 as clearly seen in Fig. 1, and the lower edge of the panels 25^a are likewise hingedly connected to the hinge lugs 18 by similar hinge members 30, it being understood that all hinged connections of the side panels with each other with the hinge lugs 18 of the bottom member B, and with the top member C are obtained by duplicated members 30.

The top member C, Fig. 10, is of screen wire 31, like that of the crate ends E or crate sides F and has longitudinal U-shaped binding strips 32 and pintles 33, the former of which are notched for the aforesaid double hinge members 30, as seen at 34 in Fig. 10. The end binding strips 35 for the top C are disclosed in detail in the fragmentary section Fig. 15, and in this view it will be seen that these strips 35 have a

downwardly bent portion 36, at each end of the said member C, to prevent undue outward movement of the upper edges of the crate ends E. The wire screen 31 of the top member C is transversely reinforced by bands 37 and 37^a and longitudinal U-shaped strips 38 and 38^a extending in parallelism between said bands 37 and 37^a. The wires in the rectangular space formed by these bands and strips are cut away, so as to produce an opening through the top member C, and this space is closed by a preferably sheet metallic door 39, having hinges 40, affixed to the strip 37 and hasps 41 embracing staples 42, Fig. 3, which latter are fastened to the strips 37^a. The said door 39 is provided for the entrance through said top C and exit therefrom of live poultry when the crate is employed as a poultry shipping crate, and when said crate is so employed, the door 39 is maintained in closed position by car seals (not shown) passing through the staples 42 aforesaid.

It is now to be observed that the crate ends E are of a width but very slightly less than the distance between the interior faces of the crate sides F, so that when the latter are in "righted" or upright position, the said crate ends E, when in likewise righted or upright position, have their vertical edges in close adjacency to the binding strips 27 on the vertical edges of the panels 25 and 25^a of the said crate sides, and that the upper edges of the said ends abut against the downwardly projecting, transverse lips 36 of the top member C.

In order to maintain the crate sides F and the ends E in their "righted" position there are provided trip locks G, Figs. 1 and 3. These trip locks are disclosed in detail in Figs. 5, 6, and 7, and comprise each a rectangular sheet metallic blank 43, best seen in Figs. 5 and 6. The said blank is of a thickness equal to the interior width of the U-shaped strips 27, and by riveting or other means, fastened therein at suitable points as seen in Figs. 1 and 3. Projecting from the outer edge of this blank contiguous of the inner edge of the strip 27 is a horizontal slot 44, which slot terminates in an upwardly or vertically extending slot 45. In substantial, horizontal alinement with the upper edge of the vertical slot 45, projecting from and fastened to the inner face of the marginal, vertical strip 20 of the crate end E is a tubular boss 46, the free end of which boss is plane with the free inner edge of the strips 27, marginal of the sides 25 or 25^a of the side member F. Journalized within this boss 46, projecting therethrough and headed at the outer end as seen at 47, Fig. 7, is a round rod 48, which rod is bent outwardly at right angles at the free end of the boss and terminates in a disk like head 49. The outward bent portion is adapted to be re-

ceived in the vertical slot 45 in the blank 43 already referred to and its entrance thereto may be explained as follows. The end E is first pressed inwardly sufficiently so as to enable the outward bent portion of the rod 48 to be rotated past the free edge of the blank 43 until the said portion is opposite the entrance to the longitudinal slot 44. The end E is now pressed outwardly, enforcing the movement of said portion 49, into said slot 44, to the vertical slot 45, after which a slight upward turning movement of the rod 48 about its axis, lodges the said outwardly bent portion in the slot 45, thereby preventing any oscillation of the end E while the said portion 49, is lodged in the said slot 45.

In order to firmly clamp the crate sides F, or, in other terms the panels 25 and 25^a, against the vertical edges of the crate ends E, the head 49 of the rod 48 is centrally apertured for the reception of a rivet or stud 50, about which stud is pivoted a lever 51 having a peripheral portion 52 disposed eccentrically to the pivot 50, so that as the said lever is rotated, its eccentric periphery will contact against the outer face of the blank 43 and enforce a "drawing together," as it were, of the ends and sides in a manner easily understood. And it is now explained that the lever 51 has an under cut portion 53, surrounding the upper edge of the blank 43 when said lever has been rotated to clamp the particular side panel and end together, so as to prevent a downward rotation of the rod 48.

It is now to be understood that as many of these clamping members G may be employed as is necessary to positively maintain the crate ends E and the crate sides F in righted position, and it will be also understood that a reverse rotation of the levers 51 may be accomplished by the application of the tip of a finger to the finger-piece 54 of the lever 51, whereupon the components comprising the clamp or clamps G may be disconnected in an easily understood manner.

In Figs. 8 and 9 I indicate the clamps G of slightly modified though equivalent construction. In the last named figures the entire clamp mechanism is disclosed as being located entirely on the exterior faces of the binding strips 20 and 27 of the crate ends E and crate sides F, respectively.

I wish now to particularly emphasize the fact that the end members or crate ends E are truly hinged to the bottom B and operate about pivots of the hinges in being rotated from the "righted" or upright position to the horizontal or knocked down position. But, on the other hand, the lower edges of the crate sides are articulately jointed to the longitudinal edges, broadly speaking, of the bottom B. In like manner the several panels comprising the individual crate sides,

are not simply hinged together, but are articulately connected, so that not only a hinged action but likewise an articulation of the parts takes place when the sides are collapsed to convert the crate into its knocked down position. The top C, essentially a unitary structure, is also, along its longitudinal edges, articulately connected with the longitudinal upper edges of the upper 10 panel of the respective side members F.

Assuming now that the crate A as a whole is in righted or operative position, as indicated in Figs. 1 and 3 and that it is desired to "knock down" the same so as to occupy 15 less space upon its return journey to the original shipper than the same crate occupied upon its journey from the shipper, all that is necessary is to "untrip" the levers 51 to release the ends E and sides F; to rotate 20 the ends E into a horizontal position; to inwardly fold upon each other the panels of the sides F by a mere pressure of the hands, and to engage the hooks 100, normally depending from the lips 36 of the cover C, 25 with thumb screws 101 located on the ends 14 and 14' of the bottom member B, in which manner the structure is secured in its collapsed or knocked down position in an evident manner.

I have hereinbefore disclosed the preferred mode of practising my invention, but I reserve the right to make such and any changes as might occur to one skilled in the art to which this invention appertains, or to 35 make any and all such alterations as may be permitted under the doctrine of equivalents.

Having thus fully described my invention I claim as new, and desire to secure to myself by Letters Patent of the United States:

1. A collapsible shipping crate, comprising, in combination, a bottom member, said bottom member being a sheet metal plate, said plate having upstanding marginal flanges, a substantially semicircular metallic trough at opposing upstanding margins of said bottom member, said troughs being secured to said upstanding margins, the outer

marginal edges of said troughs being inwardly turned, there being on the said 50 marginal edges of said troughs notches, side members, said side members being wire structures, said side members being comprised each of two articulately connected panels, the lower one of said panels being connected to 55 the notched portions in the marginal edges of said troughs, end members, said end members being metallic wire structures, said end members being hingedly connected to the upstanding marginal edges of said bottom 60 member, a cover, said cover being a metallic wire structure, said cover being articulately connected to the upper marginal edges of the upper panels of said side members, there being downwardly extending ledges on the 65 end portions of said cover constructed to overlap said end members, trip locks, said trip locks being pivotally connected to the end members and constructed to retain the several panels of the side members in upstanding position, a door in said cover, and means on said cover constructed to lock said cover to the bottom member when the crate 70 is in collapsed condition.

2. In a collapsible crate, the combination, 75 of a metallic bottom member, said bottom member being of pan-shaped contour, end members hingedly connected to said bottom member, and side members articulately connected to said bottom member, there being 80 on each side member trip locking devices constructed to detachably lock said side members to said end members, said trip locking devices including each a bent rod, one member of said bent rod being pivotally 85 connected to the end member, there being at the other end of said bent rod an eccentrically pivoted clamping member constructed to engage said side member, said clamping member being constructed to release said side member when being rotated on said bent rod.

In testimony that I claim the foregoing as my invention, I have hereunto set my hand.

JOHN J. GISEKE.
